CORPORATION OF NEW YORK.

LAPPING MECHANISM.

1,417,580.

Specification of Letters Patent. Patented May 30, 1922.

Application filed July 26, 1920. Serial No. 399,214.

To all whom it may concern:

Be it known that we, REUBEN STANLEY SMITH and THORVALD HANSEN, citizens of the United States, and residents of the city of Milwaukee, in the county of Milwaukee and State of Wisconsin, have invented certain new and useful Improvements in Lapping Mechanism (Case No. 114); and we do declare the following to be a full, clear, and exact description thereof, such as will enable persons skilled in the art to which the invention pertains to make and use the same, reference being had to the accompanying drawings for an illustration of one form of construction in which our invention has been embodied.

The invention relates to lapping presses.

In the manufacture of automobile frames, the principal frame elements are constituted of side and cross bars, which are drawn from blanks punched or cut from sheet metal plates or strips. In the formation of such bars, the side margins of the blank from which the bar is produced, are turned into flanges which stand approximately parallel to each other, and at a right angle to the central plane or web of the blank, so as to produce a reinforced bar which is channeled in cross section. Certain longitudinally projecting end portions of the flanges of the channeled cross bar, which extend beyond the limits defining the body portion of the bar, are adapted to be turned or bent into angular positions with respect to the flanges of the bar, or the web of the bar as in some types of construction.

The purpose in turning or bending such projecting end portions is to create a means whereby the side bars and cross bars entering into the construction of an automobile frame, may be conveniently connected together, to produce a permanent, unitary and rigid structure. The union of these parts is usually effected by means of rivets passing through perforations in the turned or bent projecting portions, which form ears or laps on the ends of the cross bars, and registering perforations in the side bars at the portions against which such turned end portions or ears abut. The operation of bending the end portions of the cross bars so as to form these fastening ears, is known in this art as "lapping."

The ears or laps referred to as being formed out of the projecting ends of the cross bars, may be folded so as to extend toward each other or into the channel of the cross bar, the ears in such positions standing in a plane which crosses the longitudinal axis of the said bar. Also, the fastening ears or laps, formed at the end of the flanges of the cross bar, may be bent so as to stand tandem with respect to each other, one of such ears in this arrangement extending into the channel of the cross bar, and the other extending outwardly from the bar, but both lying in the same plane. Again, the ears may extend in directions which are opposite to each other, or which radiate from the axis of the cross bar. It will be understood that the formation of the ears with respect to the cross bar, and the angle at which they stand, or the direction in which they lie, will be dependent upon the particular type of automobile frame under construction, and that the arrangement of the ears with respect to the cross bar may be changed, as desired, to meet whatever may be the needs of such particular construction. In certain other instances, the projecting end portions of the cross bar may be folded back and lapped against the flanges of which they are a part, so as to constitute a reinforcement of the cross bar at such points.

The present invention embodies mechanism for turning or bending the projecting end portions of the flanges of a cross bar from the vertical, parallel planes which they assume in the drawing operation, into others, which ordinarily will be 90° therefrom, see 90 as to construct the fastening ears or laps described. These ears or laps may be formed at the ends of the central portion or web of the cross bar, if desired, but this latter operation will not be performed by the mechanism herein disclosed.

By adaptation of our lapping mechanism, the projecting ends of the cross bar may be turned while the cross bar is still clamped between the dies of the drawing press. Our present invention, however, is intended for use independently of and apart from a drawing press, and when so used the cross bar will be presented thereto and clamped and firmly held in position during the operation of the lapping mechanism. The novel

clamping mechanism which we employ, consists of a central filler block which enters the channel of the cross bar and fills the space therein, and side members which are 5 adapted to bear with a wedging action upon the faces of the flanges and clamp such flanges against the said filler block.

The lapping mechanism is composed of a reciprocating slide bar, provided with a suitable die member having acting faces which 10 are adapted to engage the projecting ends of the cross bar, and turn or bend them into the desired angular positions with relation to the cross bar. The reciprocating slide 15 bar moves back and forth in a path into which the projecting ends of the flanges of the cross bar extend. The faces of the die members, by reason of their engagement with the sides of the said projecting end 20 portions, act to bend or flatten the said projecting portions against the central block in the channel of the bar, so that the ears thus formed extend toward each other and 25 into the channel of the cross bar. When the projecting ends of the flanges of the cross bar are to be turned in directions extending away from the bar, the lapping die will 30 serve to turn such projecting ends about the clamping members. Also, the said projecting ends may be turned so as to stand 35 tandem. In this last described operation the ear formed from one side flange will extend into the channel of the cross bar, and the ear formed from the other side flange will extend 40 away from the cross bar. To effect 45 these different results, in the operation of our invention, it is necessary only to provide the reciprocating slide bar with suitably arranged die faces. The clamping mechanism 50 serves to hold the side flanges of the cross bar against displacement during the lapping operation. The faces of the co-operating 55 clamping members are flush with each other, so as to present a plane-faced anvil 60 against which the projecting end portions of the flanges may be turned or bent, in the reciprocations of the slide bar, by the acting 65 faces of the lapping dies wiping against and over the said projecting ends, to flatten the ears against the anvil formed by the aligned 70 faces of the clamping members, when the said ears are squeezed by the pressure of the lapping dies thereon.

The novel features of our invention will be 75 pointed out in the appended claims.

In the accompanying drawings:

Figure 1 is a side view in elevation, and partly in section on the line 1—1, Fig. 2, showing a construction embodying our improved lapping mechanism, and means for actuating the dies thereof.

Fig. 2 is a horizontal sectional view thereof, on the line 2—2, Fig. 1, showing the parts somewhat enlarged, and showing also the 65 form of lapping dies used to bend the pro-

jecting ends of the flanges of the cross bar toward each other, and flatten such ends against the filler block of the clamp.

Fig. 3 is a corresponding vertical sectional view on the line 3—3, Fig. 2.

Fig. 4 is a fragmentary view, showing in plan the form of lapping dies used to bend the projecting ends away from each other.

Fig. 5 is a perspective view of one end of a cross bar, showing the ears or laps as 75 turned across the channel of the bar.

Fig. 6 is a similar view of one end of a cross bar with the said ears or laps turned in opposite direction and away from the bar.

Fig. 7 is a view similar to Fig. 4, and 80 showing the configuration of the lapping dies used for turning the ears into tandem relation.

Fig. 8 is a perspective view of one end of a cross bar, showing the tandem arrangement 85 of the ears produced by the lapping dies shown in Fig. 7.

Referring to the drawings, the base of the machine is indicated 10. From the base rises a standard 11, which supports the 90 means for clamping the cross bar 12, so that the projecting portions 13 thereof, may be properly turned or bent into an angular position with reference to the cross bar, so as to form fastening ears thereon.

Fig. 2 illustrates in plan view a construction of lapping die 14, designed to turn or bend the projecting ends of the cross bar into the channel thereof. The said die 14 is cut away at one side to form a recess 15, 100 into which the projecting ends of the cross bar extend. The end walls 16 of the said recess constitute the acting faces of the lapping die 14, and a movement of the die 14 in one direction, will turn or bend and flatten one of the projecting ears, while a reverse movement of the said lapping die, will act similarly upon the other ear.

The cross bar 12 is passed through an opening 17 in the standard 11. A clamping head 18 is guided for vertical movement on the face of the standard 11, and carries an interchangeable filler block 19, which is designed to be passed into the channel of the cross bar. The base is provided with a 115 clamping member 20, co-operating with the clamping head 18, the said clamping member being cut out at its central portion so as to provide a widened space 22, through which the projecting ends of the flanges of the 120 cross bar may be passed. The said clamping member has inclined portions 23, at the opposite ends of the space 22, against which movable wedges 24, carried by the clamping head, operate. The wedges 24, are loosely 125 supported in an undercut seat 30, in the clamping head 18, as shown in Fig. 3. When the clamping head 18 is depressed to insert the filler block 19 in the channel of the cross bar, the movement of the head 18 engages the 130

wedges 24 with the inclined portions 23 of the clamping member 20, with the result that the side flanges of the cross bar are tightly held as in a fixed position. Movement of the lapping die 14 now taking place, the projecting ends 13 of the cross bar, will be turned and flattened, as previously described. The said lapping die 14, is actuated by means of a link 25, having connection 5 with a crank 26, actuated by any suitable driving mechanism. Fig. 1 shows the crank and its connected parts in their neutral position of rest. A complete rotation of the said crank effects the formation of both ears 10 upon the cross bar.

Fig. 4 shows the configuration of the lapping die which is used to spread the projecting ends of the flanges of the cross bar, that is, to turn them in opposite directions and 15 away from the longitudinal center line of the cross bar. In this figure, the lapping bar 140 is cut away at each side so as to present a lapping die 141, provided with inclined faces 142. In the neutral position of the 20 crank 26, the part 141 is at rest between the projecting ends of the flanges of the cross bar, and in line with the channel therein. A complete rotation of the crank will act to spread 25 first one of the projecting ends of the cross bar, and then the other.

Fig. 7 shows the configuration of the lapping die which is used to turn the projecting ends of the flanges of the cross bar 12, so as to form fastening ears which stand 30 tandem to each other. The edge of the lapping bar 144 is cut away so as to present projections 145, each having inclined die faces 146, adapted to bear upon the corresponding 35 sides of the projecting ends of the flanges 40 at the end of the cross bar, and turn the said flanges into the same plane, in a single movement of the lapping bar 144, in one direction.

The lapping bar in each of the constructions illustrated, is held up to its work by 45 means of a grooved guide 27, formed upon the base 10. The said guide resists the tendency of the lapping bar to depart from its true line of movement, and the parallel faces 50 of the die portions of the bar are caused to wipe over the turned or folded projections at the ends of the cross bar, and squeeze and flatten the ears thus formed against the clamping members, to set the fastening ears 55 in the desired angular positions with relation to the cross bar upon which they are formed.

One end of the cross bar will be placed in the lapping mechanism for operation thereon 60 of the lapping dies in the manner hereinbefore described. The cross bar will then be reversed, and its other end subjected to operation by the lapping dies. The feeding of the cross bars to the lapping mechanism for 65 one operation, and their reversal for the sec-

ond operation, may be manual or automatic.

Modifications of the structural arrangements shown in the accompanying drawing may be made without departing from the spirit of our invention.

Having thus described our invention, what we claim and desire to secure by Letters Patent of the United States, is:

1. A mechanism for bending the projecting ends of a flanged cross bar, comprising 70 means for clamping the bar at the bending line, and means operating upon the said projecting ends to turn the latter about said bending line and into angular positions with relation to the longitudinal axis of the cross 75 bar.

2. A mechanism for bending the projecting ends of a flanged cross bar, comprising 80 means for clamping the cross bar at the bending line, and means acting in succession 85 upon the said projecting ends to turn the latter about the bending line of each projecting end and into an angular position with relation to the longitudinal axis of the cross bar.

3. A mechanism for bending the projecting ends of a flanged cross bar, comprising 90 means for clamping the cross bar, and a reciprocating slide provided with lapping dies adapted to bend the said projecting ends 95 into angular positions with relation to the longitudinal axis of the cross bar.

4. A mechanism for bending the projecting ends of a flanged cross bar, comprising 100 a lapping die member having a plurality of acting surfaces, each adapted to bend one of the said projecting ends into an angular position with relation to the longitudinal axis of the cross bar, and means for actuating the said lapping die member.

5. A mechanism for bending the projecting ends of a flanged cross bar, comprising 105 clamping means composed of a block to fill the channel of the bar and members bearing against the flanges of the bar, means for exerting pressure upon said members to hold the cross bar, and means for bending the said projecting ends into angular positions with relation to the longitudinal axis of the cross 110 bar.

6. A mechanism for bending the projecting ends of a flanged cross bar, clamping means composed of a filler block for insertion in the channel of the bar and wedging members exerting pressure upon the side 115 flanges of the bar, and means for bending the said projecting ends into angular positions with relation to the longitudinal axis of the cross bar.

7. A mechanism for bending the projecting ends of flanged cross bars, comprising 120 a frame, a clamping head thereon and provided with means for clamping the flanges of the cross bar at the bending line, and means for bending the said projecting ends 125 130

into angular positions with relation to the longitudinal axis of the cross bar.

8. A mechanism for bending the projecting ends of flanged cross bars, a frame, a movable clamping head provided with means to fill the channel of the cross bar and supporting also movable members bearing against the side flanges of the bar, means upon the frame co-acting with the said movable members to clamp the cross bar at the bending line, and means for bending the said projecting ends into angular positions with relation to the longitudinal axis of the cross bar.

15. 9. A mechanism for bending the projecting ends of flanged cross bars, comprising means for clamping the cross bar at the bending line, and reciprocating devices provided with lapping dies adapted to turn the said projecting ends and flatten them against the clamping means.

10. A mechanism for bending the projecting ends of flanged cross bars, comprising means for clamping the cross bar at the bending line, a lapping bar cut away at one side to provide a plurality of acting lapping die surfaces, each of which is adapted to bend one of the said projecting ends into an angular position with relation to the longitudinal axis of the cross bar, and means for actuating the lapping bar.

11. A mechanism for bending the projecting ends of flanged cross bars, comprising a frame, a lapping bar for bending the said projecting ends into angular positions with respect to the cross bar, a clamp for holding the cross bar with its ends projecting into the path of movement of the lapping bar, a fixed guide for the said lapping bar, and means for actuating the said lapping bar to first turn the said projecting ends and then flatten them against the clamp.

12. A mechanism for bending the projecting ends of flanged cross bars, comprising a frame and means thereon for holding the cross bar, a reciprocating lapping member having a plurality of acting die faces, each of which is adapted in succession to bend one of the said projecting ends into a position of angularity with respect to cross bar,

and means for actuating the lapping member.

13. A mechanism for bending the projecting ends of flanged cross bars, comprising means for clamping the cross bar at the bending line, said means including a filler block for engaging the inside surfaces of the flanges of the bar and pressure devices engaging the outer surfaces of the said flanges in line with the filler block, and means for bending the said ends into angular positions with respect to the cross bar.

14. A mechanism for bending the projecting ends of flanged cross bars, comprising clamping means including devices for filling the channel of the cross bar and for engaging the outer surfaces of the flanges at the bending line, and means for bending the said ends into angular positions with respect to the cross bar and squeezing them against the said clamping devices.

15. Clamping means for holding the flanges of a channeled cross bar in position for a bending operation, said means comprising a block adapted to fill the channel of the bar and engage the inner faces of the flanges, and wedging members adapted to bear against the outer faces of the said flanges to press such flanges against the filler block.

16. Clamping means for holding the flanges of a channeled cross bar in position for a bending operation, said means comprising a member with an opening, the end walls of which are inclined toward the bottom of such opening, a block adapted to fill the channel of the bar, and wedging members co-acting with the said inclined end walls to press the flanges against the filler block.

17. A press provided with means for holding a cross bar, lapping dies co-operating with the holding means to turn the projecting ends of the cross bar to form fastening ears, and means for actuating the dies.

In testimony whereof, we have signed our names at Milwaukee, this 22nd day of July, 1920.
